UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING.

1,148,039.

Specification of Letters Patent. Patented July 27, 1915.

Application filed March 26, 1915. Serial No. 17,128.

To all whom it may concern:

Be it known that I, ISAAC H. MILLIKEN, a citizen of the United States, residing at Aspinwall, in the county of Allegheny and 5 State of Pennsylvania, have invented certain new and useful Improvements in Couplers; and I do hereby declare the following to be a full, clear, and exact description of the invention, such as will enable others 10 skilled in the art to which it appertains to make and use the same.

My invention relates to the construction of that class of car couplings having for their object the effecting of a coupling between the cars of a train whether the same be provided with a link or shackle or an automatic vertical plane type of coupler. The demand for an efficient coupler of such a type has been created by the introduction 20 abroad of the vertical plane or Master Car Builders' type of coupler, and its substitution for the link and shackle type of couplers.

In the case of cars equipped with the link 25 and shackle couplings the buffers are two in number and are located near the opposite ends of the buffer beam or end sill of the car. As the hooks of the couplings do not extend out as far as the faces of these buffers, such hooks are commonly connected by a link device which is adapted to be adjusted by a screw to thereby assure contact between the buffers of the opposed cars.

In the case of cars equipped with the vertical plane or Master Car Builders' type of 35 coupler, the lateral buffers on the buffer beam or end sill located near the ends thereof are usually omitted and the buffering is effected by the coupler either alone or acting 40 in conjunction with a centrally disposed or platform buffer.

As heretofore constructed, to meet the conditions existing during the period of transition from one type to the other type of 45 coupling, transition couplers have been complicated, expensive to build and maintain, weak in structure, and having their elements so combined that the value of the device as a coupler will cease with the transitory demand therefor, because when disassociated its elements will fail to be of any utility 50 and will be valueless except as scrap.

The object of my present invention is to 55 obviate the disadvantages and losses hereinbefore noted and to meet the necessary re-

quirements by minimizing the coacting or combining elements and by so combining the same that after the demand for a transition coupler has ceased the hook element thereof may be disassociated from the combination 60 without material labor and without weakening or destroying the efficiency of the remaining parts, which themselves constitute a complete vertical plane coupler.

To this end, the main feature of my invention 65 involves the combination with the stem or shank of a vertical plane coupler, of a hook member mounted thereon in advance of the pivotal point of the stem and to one side of the longitudinal axis of the stem or 70 shank, whereby any draft force exerted on the hook will cause and maintain the radial lateral displacement of the stem of the vertical plane coupler.

There are other, minor, features of invention, 75 involving the particular relation and arrangement of the coacting elements, all as will hereinafter more fully appear.

In the drawings chosen for the purpose of illustrating my invention, the scope whereof 80 is pointed out in the claims, Figure 1 is a plan view of a transition coupling embodying my invention; Fig. 2 is a side elevation thereof; and Fig. 3 is a detail plan view of a portion of the device indicating the relations assumed by the parts when a link or shackle coupling is in service. 85

Like symbols refer to like parts wherever they occur.

I will now proceed to describe my invention 90 more fully so that others skilled in the art to which it appertains may apply the same.

In the drawings, 1 indicates a coupler head having a guard arm 2, pivoted knuckle 95 3, lock 4 and stem 5, all of which may be of any desired or approved form of the vertical plane or Master Car Builders' type now in use. The stem or shank 5, which is preferably formed integral with the coupler 100 head, has a pivot hole for the tail pin 6 whereby it may be attached by means of a tail pin and a spring-pocket or draft-bolt to any suitable design of draft gear so as to permit said coupler to have the required 105 lateral or radial movement in a supporting carrier iron. The draft gear and carrier iron are not shown in full because they are well and universally known to those skilled in the art and may be of any desired charac- 110

ter, but the direct connection of the coupler stem 5 with the draft gear by means of the tail pin 6, is indicated by showing a portion 10 of a spring pocket.

5 At one side of the longitudinal axial line of the coupler stem or shank 5 and in advance of the pivotal point 6, I attach a hook 7 that is adapted to coöperate with a coupling link or shackle of the usual form; and 10 for this purpose I prefer to form the stem or shank 5 with laterally projecting ears or flanges 8 which are pierced for the passage of a pivot pin 9, whereby the hook 7 is so mounted on the stem or shank as to be capable of swinging laterally toward and from the shank.

The pivoted connection between the coupler shank 5 and the shackle engaging hook 7 permits the hook to assume a position close 20 to the side of the stem or shank when not in service; and when in service the draft forces thereon will, by reason of the relation of the hook to the pivotal point 6 of the stem 5, maintain the shank or stem of the vertical 25 plane coupler out of the line of draft, as indicated in Fig. 3 of the drawing.

When a transition coupler is no longer required, the link or shackle engaging hook 7 can be removed by withdrawing the pin 9, 30 leaving a complete, strong, cheaply maintained and efficient vertical plane or Master Car Builders' type of coupler.

In the following claims any element which acts directly on the followers of the draft 35 gear, as for instance a draft bolt, is to be considered the equivalent of a spring pocket.

Having thus described my invention, what I claim and desire to secure by Letters Patent is:

40 1. The combination with a vertical plane coupler having a stem, of means whereby said stem may be pivotally connected to a railway vehicle, a hook member mounted on said stem at one side of the longitudinal 45 axis thereof and in advance of the means for pivotally connecting said stem to the railway vehicle.

2. The combination with a vertical plane coupler having a stem, of means whereby 50 said stem may be pivotally connected to a

railway vehicle, and a hook member pivotally mounted on said stem at one side of its longitudinal axis.

3. The combination with a vertical plane coupler having a stem, of means whereby 55 said stem may be pivotally connected to a railway vehicle, and a hook member pivotally mounted on said stem at one side of the longitudinal axis of the latter and in advance of the means for pivotally connecting 60 said stem to the railway vehicle.

4. The combination with a vertical plane coupler having a stem, of means whereby 65 said stem may be pivotally connected to a railway vehicle, members projecting laterally from said coupler stem adapted to be connected to a hook member, and a hook member pivotally connected to said laterally projecting members.

5. The combination with a vertical plane 70 coupler having a stem, of means whereby said stem may be pivotally connected to a railway vehicle, and a hook member connected to said stem and movable toward and from the stem in the plane of movement 75 thereof.

6. The combination with a vertical plane coupler having a stem, of means whereby 80 said stem may be pivotally mounted on a railway vehicle, and a hook member which is secured to said stem and which is movable with said stem and also movable with respect thereto.

7. The combination with a vertical plane coupler having a rigidly connected head and 85 stem, of a hook member detachably connected to said stem, said stem being provided with means whereby it is adapted to be connected to the draft gear of a railway vehicle, and said hook member being connected to 90 said stem in advance of the means for connecting said stem to the draft gear.

8. The combination with a vertical plane coupler having a rigidly connected head and 95 stem, of a hook member mounted on said stem, a draft gear spring pocket engaging said stem, and means for connecting said coupler stem and spring pocket.

In testimony whereof I affix my signature.
ISAAC H. MILLIKEN.
